(57)

CLAIM

The ornamental design for a nozzle, as shown and described.

DESCRIPTION

FIG. 1 is a top, front, right side perspective view of a nozzle; FIG. 2 is a front elevation view thereof; FIG. 3 is a rear elevation right view thereof; FIG. 4 is a left side elevation view thereof; FIG. 5 is a right side elevation view thereof; FIG. 6 is a top plan view thereof; and, FIG. 7 is a bottom plan view thereof.

The broken lines in the drawings represent portions of the nozzle that form no part of the claimed design.

The nozzle is shown with a symbolic break in its length. The appearance of any portion of the article between the break lines forms no part of the claimed design.

1 Claim, 6 Drawing Sheets(56)
